[57] CLAIM

The ornamental design for boat trailer tongue support or the like, substantially as shown.

DESCRIPTION

FIG. 1 is a rear elevational view of the boat trailer tongue support showing my new design;

FIG. 2 is a right side elevational view thereof;

FIG. 3 is a top view thereof;

FIG. 4 is a bottom view thereof;

FIG. 5 is a cross-sectional view taken along line 5—5 of FIG. 1;

FIG. 6 is a fragmentary cross-sectional view on an enlarged scale taken along line 6—6 of FIG. 5; and

FIG. 7 is a fragmentary cross-sectional view on an enlarged scale taken along line 7—7 of FIG. 3.

FIG.1**FIG. 2****FIG.3****FIG. 4****FIG. 6****FIG. 5****FIG. 7**
